UNITED STATES PATENT OFFICE

158,192

ORNAMENT FOR A CAKE OR THE LIKE

Haven W. Hettick, Lynwood, Calif.

Application October 18, 1948, Serial No. 149,150

Term of patent 14 years

(Cl. D29—1)

To all whom it may concern:

Be it known that I, Haven W. Hettick, a citizen of United States of America, residing at Lynwood, in the county of Los Angeles and State of California, have invented a new, original, and ornamental Design for an Ornament for a Cake or the like, of which the following is a specification, reference being had to the accompanying drawing, forming a part thereof.

In the drawing:

I claim:

The ornamental design for an ornament for a cake, or the like, as shown.

HAVEN W. HETTICK.
